(57) **CLAIM**

The ornamental design for a box to collect precious metal filings or shavings, as shown and described.

DESCRIPTION

FIG. 1 is a top plan view of a box to collect precious metal filings or shavings in accordance with the invention. That which is depicted in broken lines forms no part of the invention;

FIG. 2 is a front view thereof, which is identical/symmetric to the rear view thereof;

FIG. 3 is a left side view thereof, which is identical/symmetric to the right side view thereof; and,

FIG. 4 is a cross-sectional view thereof across line 4—4 of FIG. 1.

The bottom is flat and unornamented.
